UNITED STATES PATENT OFFICE.

CARL F. WALZ, OF MINNEAPOLIS, MINNESOTA, ASSIGNOR TO DURKEE-ATWOOD COMPANY, OF MINNEAPOLIS, MINNESOTA, A CORPORATION OF MINNESOTA.

HEATER FOR ENGINE WATER CIRCULATING SYSTEMS.

Application filed July 2, 1928. Serial No. 229,794.

This invention relates to improvements in heaters for water circulating systems of internal combustion engines, whereby the cooling medium may be kept warm in cold weather, when the engine is not running, and also whereby the circulating cooling medium of the engine may be heated to warm the engine before initially starting the latter, thereby facilitating engine starting.

10 An object of the invention is to provide a heater for engine water circulating systems adapted to be connected in a pipe of the circulating system and having means for laterally adjusting it with respect to the pipe, in which it is connected, to facilitate the installation of the device on the engine.

15 A further object of the invention is to provide a heater for engine water circulating systems, comprising a tubular supporting member having a suitable heating means mounted therein and adapted for attachment with an electric light socket, or other source of electrical energy, and the supporting member having eccentric means being provided at 20 each end thereof, permitting lateral adjustment thereof with respect to the water circulating pipe in which it is connected, so that the axis of the heater supporting member may be off-set from the axis of the pipe without interfering with the operation of the heater, such adjustment of the heater being necessary when installed in some circulating systems because of the lack of room or clearance between the water circulating pipe and 25 the engine block.

30 A further and more specific object of the invention is to provide an electric heater for engine water circulating systems, comprising a tubular flexible supporting member having an eccentric bushing inserted in each end thereof, each provided with an aperture adapted to receive an end of the water circulating pipe in which the heater is mounted, and a suitable clamping means being provided at each end of the supporting member for securing the heater in adjusted positions upon the pipe, and to contract the parts to 35 prevent leakage between the joints thereof.

35 Other objects of the invention will appear 40 from the following description and accompanying drawings and will be pointed out in the annexed claims.

In the accompanying drawings, there has

been disclosed a structure designed to carry out the various objects of the invention, but it is to be understood that the invention is not confined to the exact features shown as various changes may be made within the scope of the claims which follow.

40 In the accompanying drawings forming part of this specification—

Figure 1 is a view illustrating a portion of an internal combustion engine with the invention applied thereto;

Figure 2 is an enlarged longitudinal section view of the improved heater, showing the means provided at each end thereof for laterally adjusting it;

Figure 3 is a perspective view illustrating one of the eccentric bushings removed from the device;

Figure 4 is an end elevation, showing the device mounted in a water-circulating pipe, and the heater laterally adjusted with respect to the pipe because of lack of clearance between the pipe and the engine block.

45 In the selected embodiment of the invention here shown, for purposes of disclosure, there is illustrated in Figure 1, a portion of an internal combustion engine comprising the usual cylinder block 2, crank case 3, cooling radiator 4 having a pipe connection 5 connected with the lower portion thereof, and a pipe 6, connected to the cylinder block as shown in Figure 1. The pipes 5 and 6 are 50 usually connected together by means of a flexible hose connection to permit a slight movement of one pipe with respect to the other, caused usually by engine vibration. This is common practice in most automobile 55 engines, because the radiator is not supported directly upon the engine, but upon the vehicle chassis, and the flexible connection usually interposed between the pipes 5 and 6, permits limited relative movement between the pipes, 60 caused by engine vibration.

65 The novel heater featured in this invention is adapted to be interposed between the pipes 5 and 6 in place of the usual hose connection, above referred to.

70 The invention comprises a tubular supporting member 7, preferably of flexible material, such as rubber hose, and has a suitable heating element 8 mounted therein and supported in a wall of the member 7, as shown in Figure 2. The heating element comprises a

cylindrical casing 9 having a relatively smaller member 11 mounted therein which is provided with outwardly flared end portions 12, adapted to be fitted into the ends of the cylindrical casing 9 and secured thereto by such means as soldering or electric welding. The wall of the relatively smaller member 11 is spaced from the wall of the casing 9, to provide an annular space adapted to receive the heating element 8. A threaded nipple 13 is suitably secured to the wall of the casing 9 and is adapted to be inserted through an aperture 14, provided in the wall of the supporting member 7. Washers 15 are mounted on the nipple 13 and are placed respectively inside and outside of the wall of the member 7. The outer washer is engaged by a clamping nut 16 received in threaded engagement with the nipple 13, and which also forms a finishing cap for the nipple 13 as shown in Figure 2. The nipple is provided with a bore 17 adapted to receive the cable conductor 18 which has one end connected with the heating element 8, and has its other end connected with a plug 19 adapted for connection with an electric light socket.

An important feature of this invention resides in the novel means provided for laterally adjusting the supporting member 7 with respect to the circulating pipes 5 and 6 of the engine cooling system. The means for thus adjusting the heater is best shown in Figure 2, and comprises a pair of eccentric bushings 21, one mounted at each end of the supporting member 7. Each bushing is provided with an aperture adapted to snugly receive the end of its complementary water pipe. A suitable hose clamp 22 is provided at each end of the supporting member 7 and provides means for tightly clamping the parts against the peripheries of the pipes 5 and 6 to secure the heater in proper position thereon, and also to prevent leakage of the cooling medium between the pipes and the heater.

Figure 4 illustrates an installation wherein in the water circulating pipes 5 and 6 are arranged relatively close to the crank case 3 of the engine. When mounting the heater in the circulating system of an engine having the pipes 5 and 6 thus arranged, the axis of the heater or tubular member 7 is off-set from the axis of the pipes 5 and 6, as shown in Figure 4, to provide clearance for the supporting member 7 between the water circulating pipes and the engine crank case or block. It will therefore be seen that by means of the novel adjusting means provided at each end of the supporting member 7 of the heater, that the latter may be relatively adjusted with respect to the pipes 5 and 6 to facilitate installation in the water-circulating system of the engine, and also whereby the heater may be conveniently fitted between the adjacent ends of the two pipes 5 and 6, regardless of whether they are in exact axial alignment or not.

The eccentric bushings 21 are preferably of flexible material such as rubber, and are snugly fitted into the ends of the tubular supporting member 7. Thus, when the device is connected in the circulating pipes, as shown in Figure 2, and the hose clamps are tightened, the parts encircled thereby will be contracted against the peripheries of the pipes 5 and 6, which usually are of metal, thereby securing the heater in the circulating system, and, at the same time, providing means for readily removing the heater therefrom during the summer months, if desired. The device is very simple and inexpensive and may be mounted in any standard type of water circulating system in a comparatively short length of time.

I claim as my invention:

1. A heater for engine water circulating systems, including a supporting member adapted to be interposed in a pipe of the circulating system and having means therein for heating the water, and means for laterally adjusting the heater with respect to said pipe.

2. A heater for engine water circulating systems, including a supporting member adapted to be connected in a pipe of the circulating system, means in said supporting member for heating the water, and eccentric means for laterally adjusting the supporting member with respect to said pipe.

3. A heater for engine water circulating systems, comprising a supporting member adapted to be connected in a pipe of the circulating system, heating means in said supporting member, and eccentric means at each end of the member for laterally adjusting it with respect to said pipe.

4. A heater for engine water circulating systems, comprising a flexible tubular supporting member, a heating unit mounted therein and having means for connection with a source of electrical energy, and an eccentric bushing inserted in each end of the supporting member and each adapted to be connected with a pipe of the circulating system, said eccentrics providing means for laterally adjusting the heater with respect to said pipe.

5. A heater for engine water circulating systems, comprising a flexible tubular supporting member, a heating unit mounted therein and having means for connection with a source of electrical energy, an eccentric bushing inserted in each end of the supporting member and each adapted to be connected with a pipe of the circulating system, said eccentrics providing means for laterally adjusting the heater with respect to said pipe, and means for securing the heater in adjusted positions.

6. The combination with an internal combustion engine comprising a water jacket, a water-cooling radiator, and pipes connected

with said jacket and radiator, of a water heater and circulator, comprising a tubular member adapted to connect together said pipes, said tubular member having flexible bushings 5 detachably mounted therein provided with apertures adapted to receive the terminals of said pipes, and means for contracting said bushings to provide leak-proof joints between the bushings and pipes, said bushings being interchangeable whereby the heater 10 may be fitted to pipes of different diameters.

In witness whereof, I have hereunto set my hand this 28th day of June, 1928.

CARL F. WALZ.
